Attorney.

UNITED STATES PATENT OFFICE.

HERBERT W. PRATT, OF STREATOR, ILLINOIS.

VEHICLE-TONGUE.

SPECIFICATION forming part of Letters Patent No. 356,232, dated January 18, 1887.

Application filed November 27, 1886. Serial No. 320,041. (No model.)

To all whom it may concern:

Be it known that I, HERBERT W. PRATT, a citizen of the United States, residing at Streator, in the county of La Salle and State 5 of Illinois, have invented certain new and useful Improvements in Vehicle-Tongues; and I do hereby declare that the following is a full, clear, and exact description of the same, reference being had to the annexed drawing, making a part of this specification, and to the letters and figures of reference marked thereon.

The present invention has relation to the tongues or poles of vehicles; and the object thereof is to provide an attachment to the forward end of the tongue or pole, whereby the strain thereon is relieved, thus rendering it less liable to break; also removing the heavy pressure made by the collars on the necks of the horses, and takes the strain from the wagon 2c or vehicle.

A further object of the device is to so construct it that when going over obstructions the forward and backward motion is made perfectly easy, and in going downhill all the unpleasant jolting is relieved and the driving of the team rendered more pleasant and agreeable, as the horses can travel with more freedom and ease. These several objects above enumerated I attain by the construction substantially as shown in the drawings, and hereinafter described and claimed.

In the accompanying drawing, which represents a longitudinal section of my invention, A designates a metal tube having at one end 35 a flaring socket, B, in which fits the end of the tongue or pole, and the front or forward end of said tube has exterior screw-threads, a, with which engages the thimble C, also having screw-threads upon its interior, as shown. 4c Over the tube A, near its forward end, is loosely placed a sleeve, D, and between the sleeve and socket B is a coiled spring, E, one end of said spring bearing against the rear edge of the sleeve D and the other end of the spring bearing 45 against an annular shoulder, b, formed on the tapering socket B. The spring E, as will be seen, is flat upon its interior side, in contradistinction to the ordinary round wire spring, thus keeping itself in better position around the 50 exterior of the tube A, possessing increased

strength and durability, and sliding on the tube more easily when pressure is brought against it; also removing the danger of the several coils of the spring working out of their relative position by constant use. The coils of the spring 55 may be brought nearer to or farther from each other, to regulate its tension by means of the thimble C, which may be adjusted on the end of the tube A by means of the screw-threads hereinbefore described.

The leather on the neck-yoke of the harness strikes the annular shoulder c and the sleeve works against the spring E, the sleeve working back and forward, according to the pressure from behind or the pressure placed 65 upon it by the wagon or other vehicle. It will be noticed that the pressure of the spring is in a direction toward the horses, thereby relieving the strain on the tongue or pole and the vehicle.

The annular shoulder c may be dispensed with and the sleeve D provided with arms extending out laterally therefrom for attaching thereto certain portions of the harness, thus adapting the device to backs and double carriages, these changes being made without departing from the principle of my invention, and the tongue or pole, if preferred, may extend through the tube and into the thimble, as found preferable.

Having now fully described my invention, what I claim as new, and desire to secure by Letters Patent, is—

A device for attachment to the ends of vehicle tongues or poles, consisting of a tube 85 having a shoulder at its rear end and screw-threaded at its front end, in combination with a screw-threaded thimble engaging with the screw-threaded end of the tube, a sliding sleeve placed over said tube, also a spring located between the sleeve and shoulder of the tube and coiled around the latter, as set forth.

In testimony that I claim the above I have hereunto subscribed my name in the presence of two witnesses.

H. W. PRATT.
